UNITED STATES PATENT OFFICE.

JOHN F. PETERSON, OF CHICAGO, ILLINOIS.

DEVICE FOR FEEDING LIQUIDS.

1,289,893.

Specification of Letters Patent. Patented Dec. 31, 1918.

Application filed February 23, 1918. Serial No. 218,747.

To all whom it may concern:

Be it known that I, JOHN F. PETERSON, a citizen of the Government of Russia, residing at Chicago, in the county of Cook 5 and State of Illinois, have invented certain new and useful Improvements in Devices for Feeding Liquids, of which the following is a specification.

My invention relates to means for feeding 10 a constant quantity of liquid from a reservoir in a given period of time, irrespective of the quantity of liquid therein.

One of the objects of my invention is to provide a means to feed a constant quantity 15 of liquid in a given time from a reservoir, by gravitational operation, which is substantially unaffected by variation in the head, or pressure affected by the varying head, of the column of liquid.

20 My liquid feeding device is especially applicable for use in oil cups, wherein a relatively large supply of lubricating liquid, such as oil is to be contained, and which is to be fed therefrom, drop by drop, at short 25 intervals. It may, however, be used for other purposes without material change of structure.

Other objects of my invention will become readily apparent, to persons skilled in 30 the art, from a consideration of the following description when taken in conjunction with the drawings, wherein:

Figure 1 is a central vertical section of the device.

35 Fig. 2 is a broken-away elevation thereof. Fig. 3 is a top plan view of the device.

Fig. 4 is a section taken on line 4-4 of Fig. 1.

40 In all the views the same reference characters are employed to indicate similar parts.

The invention contains essentially two reservoirs, a main or superposed reservoir, within which to contain a relatively large quantity of liquid and a sub-reservoir, considerably 45 smaller in vertical extent and preferably immediately below the main reservoir, from which the liquid is to be directly fed to the part or device to be lubricated.

50 In the embodiment chosen for illustrating one form that my invention may take, 10 is the main reservoir, consisting of a glass cylinder 11, provided with heads 12 and 13. Axially of the cylinder is a tube 14, which is screw threaded at each end, as at 15 and 16. 55 The lower end of the tube is threaded into the head 13 to hold the cylinders in place and

between the main cylinder and the head is a packing ring 17 and a similar packing ring 18 is contained between the upper end of the cylinder 10 and the head 12. 60

The sub-reservoir 20 is composed of a cylinder 21 and coöperatively with the head 13 and the head 22. A casing 23 preferably forms a part of the head 22 and is screw threaded on its upper end, as at 24, for screw 65 threaded engagement with the head 13, as at 25. Packing rings 26 and 27 are contained between the respective ends of the cylinder 21 and the heads 22 and 13. The float 28 is carried in the sub-reservoir 20 and secured thereto is a tube 29 which has free axial telescopic movement in the tube 14. The upper end of the tube 29 coöperates with a port 30 made in the lower end of the tube 14, so that when the float is at its lowest 70 position the port 30 will be opened and when the float is at the position shown in Fig. 1 the port 30 will be closed by the interposition of the tube 29. When the port is open, oil will pass from the reservoir 10 into the 80 reservoir 20 and raise the float and thereby the tube 29 is raised to close the port so that a substantially constant quantity of oil is carried in the sub-reservoir 20. 75

Apertures 31 are made in the lower end 85 of the tube 14 so that the chamber within the reservoir 20 may communicate through the tube, with the upper part of the chamber in the reservoir 10, there being a port or opening 32, in the tube 14 provided for this purpose. The upper part of the reservoir 10 finds communication with the atmosphere 90 through the opening 33, which may be loosely covered by a slide 34 to prevent the dust from entering the chamber and which 95 opening is used for the purpose of filling the chamber with oil. The slide 34 has a ring bearing around the projecting end of the tube 14.

In the lower wall 22 of the reservoir 20, 100 is a valve port plug 35. The plug 35 is axially perforated, as at 36, and is provided on its upper end with a port 37 for a needle valve 38. The valve 38 is formed on the lower end of the rod 39, which extends 105 through both chambers and the tube 14, and on its upper end it is pivoted to a cam lever 40, as at 41. A cap 42 screws over the upper end of the tube 14, and is the means for adjusting the effect of the cam lever 40 upon 110 the needle valve 38 when the lever occupies its vertical position, as shown in dotted lines

as at 40'. The cap 42 is corrugated, as at 43, and a spring clip 44, which is provided with an annular part 45, serves as a means for holding the cap 40 in its adjusted position. 5 The ring of the clip 44 surrounds the tube 14 and with the slide 34 it is held in place on the cover 12 by a nut 46. The spring 47 surrounds the rod 39 and abuts against the end wall of the cap. The lower end of the 10 spring 47 rests against a washer 48 that is held on the rod 39 by a pin 49. The spring 47 yieldingly holds the needle valve in its lowest position.

When the lever 40 is raised to dotted line 15 position, as shown in Fig. 1, the needle valve 38 is thereby raised from the port 37 and opens the passage ways 36 to the extent that it is raised. If it is desired to open the valve to a greater extent, the cap 20 42 is raised by turning it anti-clockwise and the clip 44 will hold it and prevent it from turning from its adjusted position. By this means the cam end of the lever 40 will raise the needle valve 38 to a greater or less extent, and thus the effect of the needle valve 25 may be regulated.

The oil from the sub-reservoir 20 will drop through the port 37 and the opening 36, into a small cylinder 50 therebelow. The 30 cylinder consists of a casing 51 which is screwed on a threaded hub 52 that projects downwardly from the lower wall 22 of the reservoir 20. The casing is provided with openings 53 through which the oil, as it drops through the cylinder, may be observed. 35 A glass tube 54 is contained within the cylinder and the lower end of the cylinder is screw threaded, as at 55, whereby the device, as a whole, may be connected to a part 40 to be lubricated.

The tube 29 projects below the float 28, as at 56, so as to support the float from actual contact with the upper surface of the plate 22, so as to prevent it from sticking to the plate, should it, at any time, move downwardly in contact therewith. Projections 57, are provided in the upper wall of the float, so as to prevent the upper wall of the float from, in like manner, sticking to the plate 13, should the float at any time be brought into contact therewith.

Whereas I have herein shown a single embodiment of my invention, for the purpose of clear disclosure, it is manifest that 55 many changes may be made in the general arrangement and configuration of the parts within the scope of the appended claims.

Having described my invention, what I claim is:

60 1. A device of the character described comprising a supply reservoir; a co-axially

arranged sub-reservoir; a float in the latter reservoir and a valve, operable by the float, to control communication between the reservoirs to maintain constant head in the latter 65 reservoir.

2. A device of the character described comprising a supply reservoir; a co-axially arranged sub-reservoir; a float in the latter reservoir; a valve, operable by the float, to 70 control communication between the reservoirs and to maintain a constant head in the latter reservoir; a needle valve having a seat in the lower wall of the sub-reservoir and means on the top of the supply reservoir to adjust the needle valve. 75

3. A device of the character described comprising a supply reservoir; a sub-reservoir; a tube extending through the supply reservoir into the sub-reservoir, having a port opening into the supply reservoir; a float in the sub-reservoir; a tube carried by 80 said float telescopically movable in the first mentioned tube to close and open said port, in said tube, to maintain constant liquid supply in the sub-reservoir. 85

4. A device of the character described comprising a supply reservoir; a sub-reservoir; a tube extending through the supply reservoir into the sub-reservoir, having a port opening into the supply reservoir; a float in the sub-reservoir; a tube carried by 90 said float telescopically movable in the first mentioned tube to close and open the port in said tube to maintain constant liquid supply in the sub-reservoir; a needle valve 95 extending through both tubes and reservoirs to control a port in the bottom wall of said sub-reservoir.

5. A device of the character described 100 comprising a supply reservoir; a sub-reservoir; a tube extending through the supply reservoir into the sub-reservoir, having a port opening into the supply reservoir; a float in the sub-reservoir; a tube carried by 105 said float, telescopically movable in the first mentioned tube to close and open the port in the said tube, to maintain constant liquid supply in the sub-reservoir; a needle valve extending through both tubes and reservoirs 110 to control a port opening from the sub-reservoir; a threaded plug containing a passage way terminating in a needle valve port, vertically adjustable in the bottom wall of said sub-reservoir, and means, on the top 115 of said supply reservoir, for adjusting the extent of opening of said port by said needle valve.

In testimony whereof I hereunto set my hand.

JOHN F. PETERSON.
